FLEXIBLE DRIP-CUP FOR UMBRELLAS.

SPECIFICATION forming part of Letters Patent No. 406,020, dated July 2, 1889.

Application filed August 27, 1888. Serial No. 283,825. (No model.)

To all whom it may concern:

Be it known that I, GEORGE A. BEACH, a citizen of the United States, residing at Chicago, in the county of Cook and State of Illinois, have invented a new and useful Improved Flexible Drip-Cup for Umbrellas, of which the following is a specification.

My invention relates to portable drip attachments for umbrellas.

10 The object of my invention is to provide a removable drip-cup of a simple, cheap, efficient, and durable construction, which may be easily and quickly affixed to any ordinary umbrella-tip and form a water-tight joint therewith, so as to catch and hold all water dripping from the umbrella, and which at the same time shall be light and flexible and capable of being folded into small compass for convenience of carrying in the pocket when 20 not in use upon the umbrella.

To this end my invention consists in a cone or funnel shaped shell of flexible material having a tapering flexible elastic thimble portion at its apex adapted to fit over and form a tight joint with the tip or top portion of the umbrella-stick. This cone-shaped drip-cup is 25 preferably made of rubber.

The invention further consists in providing my rubber umbrella-drip with longitudinal 30 stiffening-ribs and also with a strengthening rib or bead at its upper rim to strengthen the flexible drip-cup and enable it to sustain the weight of the water caught therein.

In the accompanying drawings, which form 35 a part of this specification, and in which similar letters of reference indicate like parts, Figure 1 is a side elevation of a device embodying my invention, showing the same applied to an ordinary umbrella and in position 40 for use. Fig. 2 is a similar view, on a smaller scale, showing the umbrella extended while the flexible drip-cup is attached. Fig. 3 is a cross-section on line 3 3 of Fig. 1. Fig. 4 is a vertical section on line 4 4 of Fig. 3, and Fig. 45 5 is a partial cross-section on line 5 5 of Fig. 1.

In said drawings, A represents an umbrella, B its stick or handle, and b the tip or top portion thereof, which extends above the umbrella-frame.

50 D is my flexible cone or funnel shaped drip, having a hollow tapering thimble d at its

mouth or apex, adapted to fit over and form a tight joint with the tip or top b of the umbrella-stick. The thimble d is made slightly tapering or cone-shaped and of elastic flexible material, preferably rubber, so that the same will fit upon and form a water-tight joint with umbrella-tips b of different sizes or diameters. The entire flexible drip D, I also preferably make of rubber, the same being 55 cast or formed in a mold. The flexible drip D is provided with longitudinal stiffening, ribs d', extending from the rim to the lower end of the thimble portion d. The strengthening-ribs d' are preferably made tapering, 60 about as shown, and of a triangular cross-section, as indicated in Fig. 5. The flexible drip D is also provided with a transverse bead or strengthening-rib d' at its top or rim. This may preferably be of an approximately circular cross-section, as indicated in Fig. 4. The strengthening-ribs d' and d' serve to give the 65 flexible cup the requisite stiffness to sustain the water contained therein.

The elastic flexible drip D is applied to the 70 umbrella-tip b by slipping the same thereon, which may be done very quickly and easily, the elastic flexible tip and thimble d enabling the same to conform to, accurately fit, and form a tight joint with any ordinary umbrella-tip, 75 whatever may be its diameter. The drip may be as readily removed when it is not desired for use and folded into a compact compass for convenience of carrying in the pocket or otherwise. When applied to the umbrella-tip, 80 however, it does not interfere with the raising or extending of the umbrella, nor does it injure the neat appearance of the umbrella. On the contrary, as indicated in Fig. 2, the conical drip D forms a rather ornamental 85 finish to the umbrella and also a protection to the upper joint.

When the wet umbrella is folded, the drip 90 D serves to catch all water dripping from the umbrella, not only when the umbrella is set 95 down, but while it is being carried through the room. To empty the water from the drip D, all that is necessary is to simply incline the umbrella over a suitable receptacle, or the flexible drip may be turned back upon itself. 100

The flexible drip D is capable of being applied to and removed from any ordinary um-

brella without requiring any change in or mutilation of the umbrella or its tip.

I claim—

1. The flexible funnel-shaped drip D, having longitudinal strengthening-ribs d' , substantially as specified.

2. The flexible rubber funnel-shaped drip D, having longitudinal strengthening-ribs d' and transverse strengthening rib or bead d^2 at its upper rim, substantially as specified.

3. The flexible funnel-shaped rubber umbrella-drip D, having tapering elastic thimble d , adapted to fit over the tip of the umbrella, said funnel D being provided with longitudinal strengthening-ribs, substantially as specified. 15

GEORGE A. BEACH.
